Primary Examiner — Sandra S Snapp*Assistant Examiner* — Katherine Glennon(74) *Attorney, Agent, or Firm* — RatnerPrestia(57) **CLAIM**

The ornamental design for a watchcase, as shown and described.

DESCRIPTION

FIG. 1 is an enlarged perspective view of a watchcase showing our new design;
FIG. 2 is a front elevational view thereof;
FIG. 3 is a left side elevational view thereof;
FIG. 4 is a right side elevational view thereof;
FIG. 5 is a rear elevational view thereof;
FIG. 6 is a top plan view thereof;
FIG. 7 is a bottom plan view thereof; and,
FIG. 8 is a front elevational view of the watchcase wherein the lock tub is turned to an alternate position.
The broken lines shown in FIGS. 1, 2, 3, 4, 6, 7 and 8 illustrate portions of the watchcase that form no part of the claimed design.

1 Claim, 5 Drawing Sheets(56)
